United States Patent Office

Des. 190,763
Patented June 27, 1961

190,763

AIRCRAFT FLIGHT INSTRUMENT

Stuart L. Varner, Grand Rapids, and Donald R. De Maagd, Grandville, Mich., assignors to Lear, Incorporated

Filed July 2, 1958, Ser. No. 51,628

Term of patent 14 years

(Cl. D52—6)

Fig. 1.

Fig. 2.

FIG. 1 is a front elevational view of an aircraft flight instrument showing our new design; and

FIG. 2 is a side view thereof.

The essential features of the design reside in the full line portions.

We claim:

The ornamental design for an aircraft flight instrument, substantially as shown and described.
